(57) **CLAIM**

The ornamental design for a water filter with sleeve, as shown and described.

DESCRIPTION

FIG. 1 illustrates a perspective view of a water filter with sleeve of the new design;

FIG. 2 illustrates a front view thereof;

FIG. 3 illustrates a rear view thereof;

FIG. 4 illustrates a left view thereof;

FIG. 5 illustrates a right view thereof;

FIG. 6 illustrates a top view thereof; and,

FIG. 7 illustrates a bottom view thereof.

The broken dash-dot lines indicate portions of the water filter with sleeve that form no part of the claimed design.
